UNITED STATES PATENT OFFICE

MIKE NIKOLISH, OF WILLIAMSON, IOWA

SIGNAL FOR MINES

Application filed April 1, 1929. Serial No. 351,664.

The present invention appertains to new and useful improvements in signals and more particularly to a novel signal for use in mines. The principal object of this invention is to provide a signal of the character mentioned which can be set up in a mine to warn nearby miners of the immediate danger of a collapsing ceiling.

Another important object of the invention is to provide a signal device for the use mentioned, which because of its portable nature is capable of being readily carried about without any inconvenience. These and other very important objects of the invention will become more apparent to the reader after considering the invention as described and claimed hereinafter.

In the drawings:

Figure 1 represents a vertical sectional view through the novel device.

Figure 2 represents a side elevation of the structure in position for use.

Figure 3 is a bottom plan view of the platform removed from the supporting structure.

Figure 4 is a horizontal sectional view, taken substantially on the line 4-4 of Figure 1.

Figure 5 represents an enlarged fragmentary vertical sectional view.

Referring to the drawings, wherein like numerals designate like parts, the Figure 1 clearly shows a telescopic support for the signal means, which is generally referred to by numeral 3. The telescopic support includes a base plate 4, and an upstanding tubular section 5 thereon. A nut 6 is provided with a skirt 7 for dependency within the upper portion of the tubular section 5, and for threadedly receiving an elongated post or upper section 8 of the telescopic support.

A platform 9 is provided centrally with a depending hollow boss 10 for receiving the upper end portion of the threaded post 8. A spring 11 is disposed within the hollow boss and impinges against the upper end of the post 8.

A level or in fact any character of geometrical instrument is secured to the tubular section 5 by a clamp 13 and is adapted to be

used in determining the true perpendicular of the telescopic support in positioning the pipe in the manner shown in Figure 2.

Suitable bolts 14 support the housing 15 within which is mounted a conventional clock mechanism generally referred to by numeral 16 in Figure 5. The clock mechanism is provided with a hammer or striker 17 which is adapted to strike against the housing 15, in producing a warning sound. An arm 18 is disposed through an opening 19 in the housing 15 and has its inner end normally engaged with the usual escapement wheel of the clock mechanism.

The outer end of the arm 18 is connected to the lower end of the rod 20 which depends from the platform 9. A suitable key 21 is provided for engagement with the winding stem 22 of the clock mechanism.

In disposing this device in position, the same is contracted so that it may be easily set up between the floor and ceiling of a mine, after which the nut 16 is rotated so as to feed the section 8 and platform 9 upwardly so that the platform 9 will bear against the ceiling of the mine.

Obviously, any loosening of the ceiling will superimpose a load on the platform 9 which will cause the receding thereof and the consequent releasement of the escapement wheel 80 through the movement of the clock 20. Thus the clock will be released and the striker 17 brought into operation. Miners are thereby permitted to escape before the ceiling actually collapses.

Obviously numerous changes in the specific shape, size and materials may be resorted to in the construction of this novel signal device for mines, without departing from the spirit and scope of the invention as claimed hereinafter.

Having thus described my invention, what is claimed as new is:

1. An alarm for mines comprising a pair of telescopic sections for interposition between the floor and ceiling of a mine, a platform supported by the upper section, a signal supported by one of the sections, said platform being movable by a superimposed load to operate said signal.

2. An alarm for mines comprising a base, a vertical post on the base, a platform slidably mounted on the post and adapted to normally engage the ceiling of the mine, a
5 normally wound spring mechanism, a hammer operable by the mechanism, a trip on the platform for releasing the said mechanism when a load is superimposed thereon, and a reverberating body against which the
10 hammer may strike when the said spring mechanism is released.

In testimony whereof I affix my signature.
MIKE NIKOLISH.
